WHEEL BALANCER

George T. Hemmeter, Los Altos, Calif.
Application July 22, 1955, Serial No. 37,096

Term of patent 14 years
(Cl. D52—1)

FIG-1

FIG-2

FIG-3

FIG-4

Figure 1 is a perspective view of a wheel balancer showing my new design.

Figure 2 is a top plan view of the wheel balancer shown in Figure 1.

Figure 3 is a side elevation of the wheel balancer shown in Figure 1.

Figure 4 is a bottom plan view of the wheel balancer shown in Figure 1.

I claim:

The ornamental design for a wheel balancer, as shown.
